UNITED STATES PATENT OFFICE

FRANKLIN S. SMITH, OF BROOKLYN, NEW YORK

ELECTRIC RESISTOR

Application filed June 10, 1924. Serial No. 719,160.

My invention relates to electric current resistors of the water tube type and is of a character which adapts it for use in connection with electric currents of high voltage.

5 In the use of resistors of this type as heretofore constructed it has been found impractical if not impossible to maintain a substantially constant ohmic resistance because the flow of the current through the water column 10 or columns in the tubes causes an increase in the temperature thereof which in turn causes a decreased resistance to the flow of the current; and it has been found to be necessary to limit the operation of such resistors to 15 comparatively short intervals to prevent the boiling of the water in the tubes.

Hence the general object of the invention is to provide means whereby a water tube resistor may be maintained at a substantially 20 constant ohmic resistance.

It is also an object of the invention to provide means whereby the water supplied to the tubes may be subjected to a cooling operation whereby the temperature thereof may be prevented from rising to a height sufficient to interfere with the successful operation of the 25 resistor.

Another object of the invention is to provide means whereby the water after having 30 passed through one of the tubes of the resistor structure is subjected to a cooling action before it is caused or permitted to enter and flow through the other tube or tubes.

A still further object of the invention, 35 which is general in its nature, is to provide a simple, efficient and economical means which is adapted to maintain the water within the tubes at a temperature sufficiently low to permit of the continuous use of the resistor for 40 the purpose for which it is intended.

To these and other ends my invention comprehends the construction and operation as hereinafter described and as illustrated in the accompanying drawing in which I have 45 shown one convenient form of embodiment thereof. However, it will be understood that the invention is susceptible of embodiment in other forms of construction than that shown and that changes in the details of construction 50 may be made within the scope of the

claims without departing from the said invention.

In the drawing I have shown a sectional elevation of a structure embodying the invention.

Referring to the drawing: 1 designates a post or standard of dielectric material having a table 2 upon its upper end. An electric motor 3 and a water pump 4 are supported on the table 2. By means of a coupling 5 the 55 shaft 6 of the motor 3 is adapted to be connected with the shaft 7 of the water pump 4. The motor 3 is connected to the power line by means of a transformer 8 which is provided with the necessary insulation between the 60 primary and secondary coils to insulate the motor supply line from the high voltage resistor circuit. The water from the pump 4 is conveyed by means of a connecting tube 9 to the outer ends of the coiled tube 10. The inner end of the coiled tube 10 is connected by 65 means of an extension 11 to the lower end of a tube 12 of dielectric material, the upper end of which is connected to the lower end of a tube 13 the opposite end of which is connected to the outer end of the coiled tube 14, the inner end of which is connected by 70 means of an extension tube 15 to the upper end of a tube 16 of dielectric material parallel and of the same length as the tube 12. The lower end of the tube 16 is connected by 75 an extension tube 17 to the intake of the pump 4. The tubes heretofore mentioned other than 12 and 16 are of metal, preferably 80 copper.

As electrolytic conduction, in general, involves chemical change a chamber 20 is provided from which the evolved gases may escape at the top thereof. This chamber also 85 functions as an expansion chamber to compensate for changes in volume of the electrolyte.

The tubes 12 and 16 are connected in multiple by means of the cross-bars 21 and 22 which are connected respectively with the tubes 11 and 17 and 13 and 15.

Instead of water as the electrolyte, which is caused to circulate through the tubes 12 and 16 of solid dielectric, one of the well 100

known electrolytes, such as an aqueous solution of copper sulphate may be used.

By the use of a copper sulphate solution the resistivity may be made as desired through the range available by concentration.

In general the electrolytes have negative temperature co-efficients, however, Manganni's liquid resistor has an approximate coefficient of zero. This Manganni liquid resistor, as described in Pender's "Handbook for Electrical Engineers", 1917 edition, at page 469, comprises 121 grams mannite, 41 grams beracic acid, 0.06 gram potassium chloride dissolved in sufficient water to make one liter.

If Manganni's liquid resistor is used in my apparatus a substantially constant resistivity is maintained.

In order that the circulation of air in contact with the system of tubes may be accelerated I have inclosed the latter within a tubular member 26 of insulating material which is open at both ends as shown. If desired a fan or other suitable device, not shown, may be provided for blowing a draft of air through the tubular member 26 which, contacting with the tubes of the system, operates to cool the same.

The operation of the pump 4 causes a constant flow of the electrolyte, first through the tube coils 10 and from the latter to the resistor tube 12. From the latter the electrolyte flows through the tube coil 14 and thence through the resistor tube 16 back to the pump 4. This operation continues just as long as the pump is operated.

From the foregoing it will be seen not only that the water is cooled after it leaves one resistor tube before it enters the other by reason of the flow thereof through the intermediate tube coils 10 and 14 but also that cooling of the water and of the resistor tubes 12 and 16 is accelerated by the causing of a stream of air to flow through the tubular member 26 in contact with the tubes of the system.

By reason of the construction and operation as described it will be seen that if a given current of electrolyte flows through the two resistor tubes the temperature reaches a state of substantial equilibrium and that the resistance is practically constant as long as the temperature of the ambient air and the rate of flow of water through the system of tubes remains unchanged. It will be remembered that the conductivity of the electrolyte may be varied to meet requirements. As will be understood the resistance of the electrolyte in a resistor tube is directly proportional to its length and inversely proportional to the cross sectional area of the column of electrolyte flowing therethrough. It will be evident that if a variable resistance is desired without changing other conditions such variations may be obtained by

means of taps, not shown, at suitable points along the resistors.

It is obviously desirable that all sharp points and edges be eliminated or obviated and that all surfaces shall be rounded to such extent as may be possible or practical in order that corona may be kept down. The construction is well adapted to that end.

Having thus described my invention what I claim and desire to secure by Letters Patent is:

1. In an electric resistance device, in combination, two tubes of dielectric material of substantially equal length and adapted to have passed therethrough a liquid resistor material, a heat exchange device connected to one end of the first of said tubes to receive liquid resistor material therefrom and connected to one end of the second of said tubes to pass the liquid material, after cooling, into said second of said tubes, and a heat exchange device connected to the other end of the second of said tubes to receive liquid resistor material therefrom and connected to the other end of said first of said tubes to pass the liquid material, after cooling, thereinto.

2. In an electric resistance device, in combination, a liquid circulating system, including two tubes of dielectric material, spaced along the path of flow in said system, for receiving an electric resistor liquid, the column of liquid in each tube being adapted to form part of an electric circuit; and means for connecting the columns of liquid in said tubes in parallel, said means including means for cooling the liquid after it has passed through one of said tubes and before it passes through the other of said tubes, means for cooling the liquid after it has passed through said other of said tubes and before it passes through said one of said tubes, and means for causing a circulation of said resistor liquid through said system.

3. In an electric resistor adapted to be operated continuously with currents at relatively high voltage, the combination of two tubes of equal length of dielectric material, said tubes constituting parts of a liquid circulating system, the said system including coils of pipe connecting the adjacent ends of said tubes, and means for causing an electric resistor liquid to flow through the said system, the said liquid after it has passed through one of said tubes being caused to flow through the coils of pipe connected to one end of one of said tubes before it passes into the other of said tubes.

4. In an electric resistor adapted for continuous operation with current at relatively high voltage, the combination of a plurality of tubes of dielectric material, coiled pipes connecting adjacent ends of said tubes, an electric resistor liquid within the said dielec-

tric tubes and within the said coiled pipes, means for causing the said liquid to flow in opposite directions through the said dielectric tubes, and a tubular member inclosing 5 said tubes for guiding a cooling fluid in thermal contact with said tubes.

5. An electric resistor comprising a plurality of tubes of dielectric material of equal length arranged in parallel relation to each 10 other, coiled pipes connecting adjacent ends of said dielectric tubes, the connection of the said coiled pipes to the said dielectric tubes being such that after an electric resistor liquid is caused to flow through one of said 15 dielectric tubes it flows through one of the said coiled pipes before it is caused to flow through the other of said dielectric tubes, and means for causing the same to flow through the said tubes, substantially as described.

20 6. In an electric resistance device, in combination, a plurality of tubes of dielectric material, means connecting the exit end of one of said tubes to the entry end of another of said tubes, said means comprising metallic piping arranged substantially in coils and adapted to have an electrical connection made thereto, means for connecting the exit end of said other or second-mentioned tube to the entry end of said first-mentioned tube, 25 said means comprising metallic piping arranged substantially in coils and adapted to have an electrical connection made thereto, and means for circulating an electric-resistor-liquid through said tubes and coils.

30 7. In an electric resistance device, in combination, a plurality of tubes of dielectric material, means connecting the exit end of one of said tubes to the entry end of another of said tubes, said means comprising metallic piping arranged substantially in coils and adapted to have an electrical connection made thereto, means for connecting the exit end of said other or second-mentioned tube to the entry end of said first-mentioned tube, 35 said means comprising metallic piping arranged substantially in coils and adapted to have an electrical connection made thereto, means for guiding a cooling fluid into thermal contact with said coils, and means for 40 circulating an electric-resistor-liquid through said tubes and coils.

45 8. In an electric resistance device, in combination, a liquid circulating system made up of tubing a section of which is of dielectric material and having confined therein an electric resistor liquid, the column of liquid in said section being adapted to form part of an electric circuit, means operating independently of the heating of said column of 50 liquid by the passage therethrough of the current flowing in said electric circuit for circulating said liquid through said system, and means for causing the passage of a cooling fluid into thermal but indirect contact 55 with said resistor liquid.

9. In an electric resistance device, a liquid circulating system including two tubes of dielectric material, for receiving an electric resistor liquid metallic conduit means connecting the end of one tube with the end of 70 the other tube and adapted to have an electrical connection made thereto, metallic conduit means having a relatively large exposed heat-radiating surface for connecting the other end of one tube with the other end of the other tube, and means made of dielectric material forming a conduit about said circulating system for guiding a cooling fluid 75 in thermal contact therewith.

10. In an electric resistance device, in combination, means including a conduit of dielectric material forming a liquid circulating system having therein an electric resistor liquid, the column of liquid in which conduit is adapted to form part of an electric circuit; 80 means for making electrical connections to the column of liquid in said conduit; a pump for effecting movement of the liquid through said system; and means including a conduit of dielectric material for completing the circulating system and for preventing short-circuiting of said electrical connections.

85 11. In an electric resistance device, in combination, means including a conduit of dielectric material forming a liquid circulating system having therein an electric resistor liquid, the column of liquid in which conduit is adapted to form part of an electric circuit; means for making electrical connections to the column of liquid in said conduit; a heat exchange device for withdrawing heat from said liquid; a pump for effecting movement of liquid through said system and through said heat exchange device; and means including a conduit of dielectric material for completing the circulating system 90 and for preventing short-circuiting of said electrical connections.

100 12. In an electric resistance device, in combination, two tubes of dielectric material of substantially equal length and adapted to have passed therethrough a liquid resistor material, means for electrically connecting the columns of liquid in said tubes in parallel, a heat exchange device connected to 110 one end of one of said tubes to receive liquid resistor material therefrom and connected to one end of the other of said tubes to pass the liquid material, after cooling, into said other of said tubes, and a heat exchange device connected to the other end of one of said tubes to receive liquid resistor material therefrom and connected to the other end of said other of said tubes to pass the liquid material, after cooling, thereinto, said two tubes 115 and said heat exchange devices being connected so that the resistor liquid flows through one of said tubes in the same direction as the electric current flows through the column of liquid therein and so that the resistor liquid 120 125 130

flows, in the other tube, in a direction opposite from the flow of electric current through the column of liquid in said other tube.

In testimony that I claim the foregoing as my invention, I have hereunto signed my name this 7th day of June, A. D., 1924.
